UNITED STATES PATENT OFFICE.

OLNEY R. GILLOGLY, OF ZANESVILLE, OHIO.

ADVERTISING DEVICE.

Application filed November 6, 1922. Serial No. 599,339.

To all whom it may concern:

Be it known that I, OLNEY R. GILLOGLY, a citizen of the United States, residing at Zanesville, in the county of Muskingum 5 and State of Ohio, have invented certain new and useful Improvements in Advertising Devices; and I do declare the following to be a full, clear, and exact description of the invention, such as will enable others 10 skilled in the art to which it appertains to make and use the same.

My invention has for its object to provide an extremely simple and inexpensive, yet a very desirable arrangement for conspicuously displaying advertising cards, the device being well adapted for supporting cards used in political campaigns, which usually display a photograph of the candidate and remarks concerning him.

20 With the foregoing in view, the invention resides in the novel subject matter hereinafter described and claimed, the description being supplemented by the accompanying drawing.

25 Figure 1 is a rear elevation of an advertising device constructed in accordance with my invention;

Figs. 2 and 3 are vertical sectional views on lines 2—2 and 3—3 of Fig. 1;

30 Fig. 4 is a front elevation;

Fig. 5 is a perspective view of the card supporting frame.

In the drawings above briefly described, the numeral 1 designates a rectangular advertising card having its upper end 2 turned downwardly and rearwardly and secured against the back of the card near the vertical edges of the latter, by rivets 3 or any other suitable means, thereby forming a 35 downwardly opening pocket to snugly receive the arched upper end 4 of a card supporting frame 5 which is preferably formed of wire. The vertical legs 6 of this frame are connected near their lower ends by a horizontal wire rod 7 which may be soldered or otherwise secured thereto; and the lower 40 end of the card 1 is provided with an upwardly extended tab 8 on its rear side which engages the rear side of said rod to secure the card against the frame. The tab 8 is 45 preferably formed of a sheet of comparatively stiff cardboard and it may well be

attached to the card 1 by a single rivet or the like 9, whereby it may be swung about this rivet as a pivot when engaging it with 55 or disengaging it from the rod 7.

The lower ends of the legs 6 are adapted to be forced into the ground so that the card 1 may be supported at any desired conspicuous position, for instance, along a highway 60 or railroad track. Hence, the invention is well adapted for displaying posters of numerous kinds, particularly in territories having regulations which prevent tacking or pasting posters and the like to telephone 65 poles, buildings, etc.

As excellent results may be obtained from the simple and inexpensive construction shown, this construction is preferably followed. It is to be understood however, that 70 within the scope of the invention as claimed, numerous minor changes may be made.

What I claim is:—

1. An advertising device comprising a card having a downwardly opening pocket 75 at its upper end, a card support received at its upper end in said pocket, and means for connecting the lower end of the card with said support adjustably connected with the card and movable into and out of position 80 for engagement with the support.

2. An advertising device comprising a card having a downwardly opening pocket at its upper end and an upwardly extending tab at its lower end, and a card supporting frame having its upper end received in said pocket, said frame having a cross bar held against the card by said tab.

3. An advertising device comprising a card having its upper end folded rearwardly 90 and downwardly and secured against the rear side of said card adjacent its vertical edges, an arched frame having its upper end received between said downturned card end and the adjacent portion of the card, a horizontal rod extending between and secured to the legs of said arched frame, and an upwardly extending tab on the back of the card engaging the rear side of said rod. 95

4. An article of manufacture comprising an advertising card having a downwardly opening pocket at its upper end to receive the upper end of a card support, the lower end of said card having an upwardly ex- 100

tending tab to engage a cross bar on the card support.

5. An article of manufacture comprising an advertising card having its upper end folded downwardly against the rear side of the card and secured to the latter adjacent its vertical edges, and a support en-

gaging clip adjustably connected with the lower end portion of the card for movement into and out of an operative position. 10

In testimony whereof I have hereunto affixed my signature.

OLNEY R. GILLOGLY.
